ADOLPH G. KUPETZ, OF NEW ROCHELLE, NEW YORK, ASSIGNOR, BY MESNE ASSIGNMENTS, TO ELLIOTT-FISHER COMPANY, OF NEW YORK, N. Y., A CORPORATION OF DELAWARE.

COMPUTING MACHINE.

Application filed August 1, 1922. Serial No. 573,881.

This invention relates to transposition mechanism for computing machines, and is herein disclosed as applied to a combined typewriting and computing machine of the 5 Underwood-Hanson type.

In a machine of the type referred to, the carriage, in its step-by-step movement through a computing zone, causes a denomination-selector thereon to engage and actuate seriatim a set of pivoted jacks which depress downwardly-extending thrust-rods. The lower ends of the thrust-rods engage and acuate the rear arms of levers of graduated 10 lengths mounted on a common pivot at the bottom of the machine, and the forward ends of the levers actuate rather complicated transposition linkages, the latter acting through a set of bell-crank to advance denominational pin-bars, or computation members, seriatim 15 to bring the pins thereon into alignment with numeral-key-actuated pin-setting bars, so that, upon depression of a numeral-key, the corresponding pin on a selected pin-bar will be set for engagement by the general operator 20 for actuating the pin-bars and consequently the register-wheels. The jacks are actuated seriatim from right to left, and the pin-bars are advanced to pin-setting position in the reverse order.

30 The main object of the invention is to provide improved transposition mechanism, simple in structure, economical to manufacture, and readily applicable to existing machines.

35 According to the present invention, there may be used, for connecting the thrust-rods to the pin-bars, a set of levers having rearwardly-extending arms in engagement with and actuatable by said thrust-rods and no more 40 than a single set of bell-crank actuatable by forwardly-extending arms of said levers. These bell-crank may not only change the up-and-down movements of the forwards ends of the levers to the back-and-forth 45 movements of the pin-bars, but may also constitute a transposition device, since one set of bell-crank-arms has the reverse denominational order from the other set of bell-crank-arms. To effect this reversal, the bell-crank are in the form of graduated bails, and the bails are so formed and nested as to 50 give the desired result. It will be seen that, by the use of such bell-crank or bails, instead of the usual set of complicated link-

ages and the bell-crank through which the 55 linkages act to selectively advance the pin-bars, the number of parts has been greatly reduced, and it has been rendered possible to make this part of the denomination-selecting mechanism much more compact. 60

The set or system of computation bars is usually of substantially greater width than the set of levers actuated by the thrust-rods or denominational devices, the latter being arranged at letter-space intervals, and the 65 bail-like bell-crank are so contrived that one set of arms for actuation by the levers engaged by the thrust-rods is of substantially less width than the other set of arms for connection with the computation bars. 70

All of the bell-crank or bails are pivotally mounted on a single rod or shaft and preferably the latter is supported at its ends in two brackets, the forward ends of which are secured on the upper surface of a usual cross-bar of the computer. The usual comb-plate 75 for supporting and guiding the rear ends of the denominational rack-bars may be secured to the forward ends of the brackets.

Provision may also be made of a cover or 80 angle-member to be secured to the rear ends of the brackets, one flange overlying the rear ends of the brackets and serving as a stop to limit the rearward movement of the pin-bars, displacing arms of the bails, and the other 85 or downwardly-extending flange being provided with slots to receive the rear ends of the rearwardly-extending arms of the bails and the forward ends of the levers actuated by the thrust-rods, thereby serving to maintain 90 the proper operative relation between the levers and the rearwardly-extending arms.

To limit the forward movement of the rearwardly-extending arms of the bails, so as to 95 obtain a proper alignment between the pin-setting bars and the pins on the selected pin-bars, provision may be made of set-screws threaded in the horizontal flange of the angle-member referred to, so as to lie in the paths of said rearwardly-extending arms. It will be evident that the use of such set-screws in connection with the bell-crank or bails affords a very convenient and effective means 100 for insuring accurate positioning of the pin-bars for the setting of index pins thereon. Preferably the set-screws are arranged in two parallel lines, and, when the screws have 105

been adjusted as desired, they may be locked in such adjusted positions by a bar or plate interposed between the two rows of set-screws so as to engage flat portions on the heads of the set-screws, thereby preventing rotation of the latter. Provision may also be made of screws to hold the locking plate in position, the heads of the last-mentioned screws overlying and engaging the upper edge of the locking plate.

Other features and advantages will hereinafter appear.

In the accompanying drawings,

Figure 1 is a diagrammatic side view, partly in section, showing my invention illustrated in connection with a bookkeeping machine of the Underwood-Hanson type.

Figure 2 is a top plan view, partly in section, showing the nested transposition bails.

Figure 3 is a perspective view of the angle-member having provisions to limit the movements of the bell-crank in both directions and to maintain an operative engagement between each of the rearwardly-extending arms 25 of the bails and the forward ends of the levers for actuating the same.

Figure 4 is a perspective view of the nested bails separated from the rest of the mechanism.

In the usual Underwood-Hanson bookkeeping machine, a typewriter 11, comprising alphabet keys 12 and numeral keys 13, is mounted upon a computer 14. Depression of any one of the numeral keys 13 effects depression of a corresponding key-lever 15 and a pendant 16 pivoted at its upper end to the key-lever. The pendant 16, in its downward movement, engages an arm 17 fixed on the forward end of a shaft 18, there being one shaft 18 for each numeral key for typing a significant digit. Each of the shafts 18 has an arm 19 fixed thereon and connected with a bar 20 forming a part of a linkage which also includes a lower bar 21. These bars 21, when depressed, serve to depress index-pins 22 on selected pin-bars or denominational members 23, which are provided at their forward ends with racks 24 having the usual one-way connection with number-wheels 26 mounted on a shaft 27. The number-wheels 26 form part of a register, and the results of computations effected in the register may be read through a sight-opening 28 in the casting 29 of the computer.

During typing outside of a computing zone, the actuation of said bars 21 is idle as far as setting index-pins 22 is concerned, the pin-bars 23 being held in their rearward limiting positions by suitable means, such as springs 30, with the pins 22 out of alignment with the bars 21. Upon movement of the typewriter carriage (not shown) into a computing zone, a tappet 31 on a denomination-selector 32 will engage seriatim a series of denominational jacks 33 and swing them about

a common pivot 34, to depress adjustable thrust-rods or links 35 seriatim from right to left, the order of movement of the rods 35 being changed by suitable transposition mechanism to advance the pin-bars 23 seriatim from left to right into position to permit the pins 22 thereon to be set by the pin-setting bars 21. The denomination-selector 32 is rotatably and slidably mounted on a rod 35^a, supported on the rear of the usual type-writer carriage, and is held in proper letter-space position along said rod 35^a by means of a tooth 36 engaging in one of a series of notches in a rod 37, also supported on the rear of the carriage. Normally the denomination-selector 32 is in depressed position, but, upon entering a computing zone, a roller 38 thereon rides up on a zone-controlling roller 39 and is thereby raised into position to actuate the jacks 33.

The mechanism so far described is in general similar to that disclosed in the patent to Frederick A. Hart, No. 1,287,301, granted December 10, 1918.

In carrying out the present invention, the mechanism by which the thrust-rods 35 transmit the movement of the jacks 33 to the pin-bars 23 has been greatly simplified and the number of parts diminished to a great extent. To this end, the usual levers of graduated lengths to be actuated directly by the downwardly-extending thrust-rods, such as 35, are replaced by a series of levers 40 mounted on a pivot 41 and having their forwardly-extending arms engaging the rearwardly-extending arms 42 of a series of bell-crank in the form of nested bails 43 pivotally mounted on a rod 44 and provided with upwardly-extending arms 45, engaging pins 46 projecting laterally from the rear ends of the pin-bars 23. The bails 43 are graduated in size and are so formed and nested that the arms 45 have the reverse denominational order from the arms 42. It will be seen that the bails or bell-crank 43 not only serve to change the swinging movement of the levers 40 to the forward movement of the pin-bars 23, but constitute in themselves a transposition device between the levers 40 and the pin-bars 23. As shown in Figure 1, the nested portions of some of the bails extend forwardly from the rod 44 and the corresponding portions of the other bails extend downwardly, thus permitting the bails to be nested much more compactly than would be the case if all of these parts extended in the same direction. It will be evident that this portion of the transposition mechanism is very much simpler and contains a very much smaller number of parts than the usual mechanism, including a complicated system of transposition linkages from which movement is transmitted to pin-bars by means of an intermediate set of bell-crank.

The rod 44 is supported at its ends in 130

brackets 47 of convenient shape, these brackets being secured by suitable means, such as screws 48 to a usual cross-bar 49 of the computer 14. Preferably, the brackets 5 47 are so shaped that their forward ends have a considerable bearing on the upper surface of the cross-bar 49, and a comb-plate 50 of the usual form is secured to the forward ends of the brackets 47 by suitable means, such as 10 screws 51. The comb-plate 50 serves to guide the rear ends of the pin-bars 23 and may also be used to support the springs 30 by which the pin-bars 23 are normally held in their retracted positions.

15 In order to limit the movements of the bails 43 and to maintain the rearwardly-extending arms 42 thereof in alignment with the forwardly-extending arms of the levers 40, provision is made of a cover or angle-member 52 having a flange 53 to rest on the rear ends of the brackets 47 and to be secured thereto by any suitable means and a flange 54 extending downwardly therefrom at right angles along the rear ends of the brackets 47, the forward edge of the flange 53 serving as a stop for the upright arms 45, and the downwardly-extending flange 54 being provided with slots 55 to guide the arms 42 of the bails and the forward ends 20 of the levers 40 which underlie said arms 42. It will be evident that by the above arrangement the levers 40 and the arms 42 will be maintained in proper relation with respect to each other.

25 Obviously it is desirable to bring the pins 22 into proper alignment with the pin-setting bars 21 when the pin-bars 23 are selectively advanced, and, for this reason, it is desirable to determine to a considerable degree of accuracy the limits of the forward swinging movements of the bails 43. To this end, provision is made of a plurality of set-screws 56 threaded through openings in the flange 53 and having heads 57 which are slotted to permit adjustment by means of a screw-driver and are provided with flat lateral surfaces so that they may be set by wrenches. The screws 56 may be set to a fair degree of accuracy, and, inasmuch as they are positioned above and in alignment with the rearwardly-extending arms 42 of the bails, serve to limit the movements of the bails 43, the arms 42 of which will be brought into engagement with the lower ends 30 of the screws 56. The screws 56 are arranged in two parallel rows, and this arrangement is utilized in connection with locking the set-screws after adjustment thereof. The set-screws are adjusted to as nearly as possible the desired position and left so that flat portions of the heads of the screws of the two rows will face each other. A plate or bar 58 may then be inserted between the screws on the two rows so as to engage the inwardly-facing flat sides of the

heads 57, thus preventing turning of the screws 56. The bar 58 may be held in position by means of screws 59 having heads 60 overlapping the upper edge of the plate or bar 58, so as to clamp the latter against the 70 flange 53.

After the pin-bars 23 have been selectively advanced one by one and the digits to be indexed in the various denominations have been so indexed by depressing the proper 75 index-pins 22, a general operator 61 is actuated in the usual manner to cause a cross-bar 62 thereon to engage the lower ends of depressed index-pins 22 and thereby actuate the pin bars 23 in accordance with the number indexed and run such number into the 80 wheels 26 of the register.

Preferably the upper ends of the arms 45 are so shaped that they have upright fingers 63 to engage and advance the pins 46 and shelves 64 curved downwardly at their forward edges to insure the proper positioning of the pins 46 thereover when the pin-bars 23 are returned after actuation by the 85 general operator.

It will be evident that the novel structure substituted for the usual complicated transposition mechanism at the rear of the computer is very simple in form and contains a much smaller number of parts than the usual mechanism, and is readily applicable to machines in use in that it may be readily attached to the cross-bar 49 of the usual machine or removed therefrom.

90 Variations may be resorted to within the scope of the invention, and portions of the improvements may be used without others.

Having thus described my invention, I claim:

1. In a combined typewriting and computing machine having carriage-controlled denomination-selectors and longitudinally-movable pin-bars positioned thereby, a transposition mechanism comprising a series of uniform levers mounted on a common pivot, 105 a set of nested bell-crank pivoted adjacent to said levers, each bell-crank having a horizontal arm overlying one end of a corresponding horizontal lever and also having an offset, upwardly extending arm positioned to actuate a pin-bar of a corresponding denomination; and a flanged member mounted between the pivots of said levers and bell-cranks, one flange of said member forming a stop for the 110 upwardly extending arms of said bell-crank. 115

2. In a combined typewriting and computing machine having carriage-controlled denomination-selectors and longitudinally-movable pin-bars positioned thereby, a transposition mechanism comprising a series of horizontal levers mounted on a common pivot, a set of nested bell-cranks pivoted adjacent to said horizontal levers, each bell-crank having an arm overlying one end of a corresponding horizontal lever and also hav- 125

ing an offset, upwardly extending arm positioned to actuate a pin-bar of corresponding denomination; and a flanged member mounted between the pivots of said levers and bell-crank, one flange of said member having adjustable stops for the horizontal arms of said bell-crank.

3. In a combined typewriting and computing machine having carriage-controlled denomination-selectors and longitudinally movable pin-bars positioned thereby, a transposition mechanism comprising a series of horizontal levers mounted on a common

pivot, a set of nested bell-crank pivoted adjacent to said horizontal levers, each bell-crank having an arm overlying one end of a corresponding lever and also having an offset, upwardly extending arm positioned to actuate a pin-bar of a corresponding denomination; and a flanged member mounted between the pivots of said levers and bell-crank, said member having a depending, slotted flange forming alining guides for said levers and the overlying arms of said bell-crank.

ADOLPH G. KUPETZ.
